(57) CLAIM

The ornamental design for a LED cow pen, as shown and described.

DESCRIPTION

FIG. 1 is a front elevational view of the LED cow pen showing my design;

FIG. 2 is a rear elevational view thereof;

FIG. 3 is a left side elevational view thereof;

FIG. 4 is a right side elevational view thereof;

FIG. 5 is a bottom plan view thereof;

FIG. 6 is a top plan view thereof; and,

FIG. 7 is a front perspective view thereof.

The broken lines showing the colorations on the cow and pen are for illustrative purposes and form no part of the claimed design.
